UNITED STATES PATENT OFFICE.

JULIUS M. BRANIG, OF NEW YORK, N. Y.

MUSIC-LEAF TURNER.

SPECIFICATION forming part of Letters Patent No. 311,950, dated February 10, 1885.

Application filed December 12, 1883. (No model.)

To all whom it may concern:

Be it known that I, JULIUS M. BRANIG, of the city, county, and State of New York, have invented a new and useful Improvement in 5 Music-Leaf Turners; and I do hereby declare that the following is a full and exact description thereof, reference being had to the accompanying drawings, and to the letters of reference marked thereon, making a part of this 10 specification.

My invention relates to music-leaf turners wherein a cord is attached to the leaf or leaves, and is actuated by suitable mechanism to draw the leaf over from one side to the other.

15 The object of my invention is, mainly, to provide improved means for actuating the cord or cords, for supporting and guiding the same, for connecting their ends with the leaves, and for holding the leaves firmly upon the stand 20 while they are being turned. It consists in the improved devices for accomplishing these ends, hereinafter particularly specified.

In the accompanying drawings, Figure 1 is 25 a perspective view of my improved music-leaf turner, shown as attached to a piano; Fig. 2, a detail in perspective and a longitudinal section of one of the clips for connecting the end of the cord with the leaf detached; Fig. 3, a view in elevation of the cylinder for operating 30 detents, shown by dotted lines, to release successively the spools upon which the separate cords, each connected with one of the music-leaves, are wound; Fig. 4, a section through one of the spools detached, illustrating 35 its inclosed spiral spring; and Fig. 5, a detail in perspective of the slotted rod for holding ends of the cords.

A standard, A, is secured to the music stand or instrument B in any suitable manner, to 40 hold it in an upright position. The upper end of the standard supports a box, C, within which a frame, D, provides bearings for shafts E F, arranged in a horizontal position one above the other. The shaft E supports a series of spools or bobbins, E' E'' E''', &c., that 45 are connected with the shaft by spiral springs e, which permit the spools to turn a limited number of revolutions upon the shaft, and when released will return the spools to their 50 normal position. The spools are each provided with cords e' e'' e''', &c., wound thereon, and whose outer ends, after being led through a supporting device, are attached in a simple manner to the upper right-hand corner of the leaves of music. The shaft F supports a drum, 55 F', provided with pins f' f'', &c., arranged spirally thereon to project from its surface, and bear upon spring-actuated detents or pawls G, hinged or secured at their lower ends to the box, and adapted to bear, each at its upper 60 end, with an elastic pressure upon the periphery of one of the spools, so as to check thereby the action of the spiral spring, and thus prevent the recoil of the spool until the detent is pressed away from it. Ratchet-teeth 65 g, formed upon the periphery of the spools, may provide a more positive means for holding the spools in position. A ratchet-wheel, H, having a number of teeth to correspond with the number of pins f' upon the drum 70 F', is secured to the shaft F, and is revolved by an oscillating pawl, h, secured to the upper end of a vertical rock-shaft, H', which passes up through the standard A, (see dotted lines,) made to partially rotate back and 75 forth by the engagement of one end of a reciprocating spring-actuated bar, H'', with an elbow on its lower end. The bar H'' is arranged to slide beneath the key-board of the piano, and to extend within reach of the knee 80 of the performer, so that it may be readily operated in a simple and effective manner without the employment of the hands. Each reciprocation of the bar H'' serves to move the ratchet-wheel H a single interval, and thereby 85 bring one of the pins upon the drum to bear against its detent or pawl and press it away from engagement with its spool. When the spool is thus relieved of pressure or engagement with the detent, its inclosed spiral spring 90 will exert itself and revolve the spool upon the shaft E until the cord is wound upon it the usual or required number of revolutions. The pawl h is automatically withdrawn from the ratchet-wheel H by means of a suitable 95 spring. The end of the shaft F is provided with a milled head, F'', which affords means for setting the machine, and also for operating the spools by hand when desired. The cords are held in proper relation to each other and 100 to the music-leaves by means of a rod, I, provided with holes in its outer end, through

which the cords are led. The rod admits of adjustment upon the standard, so that its perforated end may be supported in any desired position to suit the size of the music leaves 5 and their position upon the stand, and this adjustment is effected by passing the rod diametrically between two hemispherical segments or divisions of a spherical block, I' I', which are pressed together and supported between 10 spring plates or brackets I¹, secured to the upper end of the box C, and clamped firmly together by a set-screw, I³, so as to hold the divided spherical block in any desired position between them. The segments fit circular openings i' formed in the brackets, which serve to prevent the displacement of the spherical block, and at the same time allow sufficient movement thereof to permit its required adjustment. When the segments I' I' are unclamped, 15 the adjustable rod I may be freely moved longitudinally between them, or clamped at any desired part of its length, while the universal joint formed by the divided spherical block I' I' will admit of a vertical or lateral movement of the outer perforated end of the rod, to hold it closely to or away from the face of the music, and near the upper and left-hand corner thereof. The ends of the cords e' e², &c., are led systematically through a slit 20 cut longitudinally in the end of a short bar, K, supported by a rod, K', over the right-hand corner of the leaves of the music-book to be turned, said rod K' being secured to and upheld by a clamp, K², adapted to engage the edge 25 of the book, or which, where loose sheets are to be turned, may be fastened to the music-rack upon which they rest. After passing through the slit which confines them in such manner as that when drawn upon they will readily slip 30 out therefrom the free ends of the cords are secured to the clips M, (see Fig. 2,) formed of tapering sheet-metal plates, the smaller ends of which are looped over through an opening in the wide end of the plate, and are secured 35 to button-pads m, which are pressed against the wide end of the plate by the elasticity of the loop, and will thus serve to clip or hold the leaves between the said pad and the end of the plate with an elastic pressure. When 40 the cords are wound upon the spools, the clips will be drawn up closely to the perforation in the end of the guide-rod I, and will prevent their withdrawal entirely therefrom.

The music may be supported upon a ledge 45 or shelf, L, provided with a central arm, L', hinged thereto, which may be held in an upright position, as shown in Fig. 1 of the drawings, or may be folded down upon the shelf when not in use. The upper end of the arm 50 L' is notched at l, and a cord secured to the shelf L, or to the lower end of the arm, may be drawn up over and upon the arm, and led at its upper end through the notch l, and secured by means of a knot or button upon the extremity of the cord, serving to prevent its accidental withdrawal from the notch. This

will provide a simple means of holding the music upon the support, allowing the leaves to be freely turned, and yet admitting of the ready removal of the music from the stand. 70 The cord may be elastic, and its flexibility prevents it from injuring the music, as is the case with rigid attachments.

The operation of the devices above described will be understood from the description given. 75 One leaf after another may be quickly turned by the simple reciprocation of the rod operated upon by the knee of the performer, which releases the spool of the leaf to be turned, and thus allows the cord to be wound up automatically upon the spool far enough to draw the leaf from the right to the left hand side of the music-support. The tension of the spring in the spool will suffice to draw the cord out of the slit in the supporting-bar K, and to pull 80 the leaf over. As separate cords are employed for each leaf, the springs that actuate the spools require but limited movement.

I am aware that a single cord connected by clips with the separate leaves of music and 90 wound upon a drum has been heretofore employed, and do not broadly claim such device.

I claim as my invention—

1. In a music-leaf turner, a series of spools provided with cords which may be attached 95 at their ends to separate leaves of music, in combination with means for mechanically turning the spools to wind the cords, and a series of detents operated successively to release the spools and turn the leaves, substantially 100 as described.

2. The combination of the standard A, the horizontally-reciprocating bar and knee-pedal H², the vertical rock-shaft H', the pawl h, the notched wheel H, and tripping-cylinder F', 105 the detents G, and cord-spoils E' E², &c., substantially as and for the purpose described.

3. In a music-leaf turner wherein a cord or cords are employed to turn the leaves, the combination, with the cord, of a longitudinally-adjustable guide-rod, I, through the end of which the cord passes, and which is secured to the frame of the machine and held thereon in any desired position, substantially as and for the purpose described. 110

4. In a music-leafer turner wherein a cord or cords are employed to turn the leaves, the combination, with the cord, and with an adjustable guide-rod, I, through the end of which the cord is led, of a stationary slotted bar, K, upheld over the upper corner of the leaf to be turned, and adapted to engage and hold the cord over the leaf, substantially in the manner and for the purpose herein set forth. 115

5. The combination, with the frame or standard A, of one or more spools and cords and a guide-rod arranged to hold and guide each cord and to be secured by universal joints in any desired position relatively to the frame or standard, substantially in the manner and for 120 the purpose herein set forth.

6. The combination, with suitable mechan-

ism for operating a cord in a music-leaf turner, of the guide-rod I, through the end of which the cord is led, hemispherical bearings I' I', through which the rod passes, and clamping-
5 plates I¹ I², supporting and securing said bearings, substantially as and for the purpose described.

7. A clip, M, for securing turning-cords to music-leaves, consisting of a tapering elastic
10 plate having its narrow end looped and passed through an opening in its wider end, and which

terminates in a button-pad to bear against said wider end, substantially as and for the purpose described.

In testimony whereof I have signed my name 15 to this specification in the presence of two subscribing witnesses.

J. M. BRANIG.
